US00D586209S

(12) **United States Design Patent**
Cadmus et al.

(10) **Patent No.:** **US D586,209 S**
(45) **Date of Patent:** **** Feb. 10, 2009**

(54) **BLANK FOR A CD PERIODICAL INSERT**

(76) Inventors: **Charles Cadmus**, 10 Woodmere La., Tenafly, NJ (US) 07670; **Gary Lenkeit**, 7 Coventry Ct., Croton On the Hudson, NY (US) 10520

(**) Term: **14 Years**

(21) Appl. No.: **29/293,863**

(22) Filed: **Dec. 14, 2007**

(51) **LOC (9) Cl.** **09-03**

(52) **U.S. Cl.** **D9/433**

(58) **Field of Classification Search** **D9/430-433, D9/414, 417, 420-423, 759; 206/45.21, 206/45.29, 476, 525.1, 526, 750, 763, 774, 206/784, 308.1, 308.3; 229/100, 101, 103.3, 229/117, 117.01, 117.03-117.08, 120.02, 229/120.08, 120.13-120.18, 120.31, 120.37, 229/125.09, 125.15, 125.29, 126, 138, 155, 229/170, 221, 222, 247, 902, 904, 917, 933-937, 229/942, 145, 212**

CLAIM

The ornamental design for a blank for a CD periodical insert, as shown and described.

DESCRIPTION

FIG. 1 is a top perspective view of a blank for a CD periodical insert showing our new design.

FIG. 2 is a top plan view thereof.

FIG. 3 is a bottom plan view thereof.

FIG. 4 is a left side view thereof.

FIG. 5 is a right side view thereof.

FIG. 6 is a bottom edge side view thereof; and,

FIG. 7 is a top edge side view thereof.

The broken lines in the drawing represent unclaimed parts of the design and do not form part of the claimed design.
